S. P. WILBUR

ENGINE PRIMING DEVICE

Filed Oct. 3, 1919

INVENTOR.

Samuel P. Wilbur

BY *Chester W. Braselton*

ATTORNEY

UNITED STATES PATENT OFFICE.

SAMUEL P. WILBUR, OF TOLEDO, OHIO, ASSIGNOR, BY MESNE ASSIGNMENTS, TO THE ELECTRIC AUTO-LITE COMPANY, OF TOLEDO, OHIO, A CORPORATION OF OHIO.

ENGINE-PRIMING DEVICE.

Application filed October 8, 1919. Serial No. 328,268.

To all whom it may concern:

Be it known that I, SAMUEL P. WILBUR, a citizen of the United States, residing at Toledo, in the county of Lucas and State of Ohio, have invented certain new and useful Improvements in Engine-Priming Devices, of which I declare the following to be a full, clear, and exact description.

This invention relates to priming devices for internal combustion engines which normally operate on a fuel which is not readily vaporized when the engine is started and is cold.

Difficulty is often experienced in starting internal combustion engines when they are cold particularly those burning the less volatile fuels and to overcome this difficulty, it is common practice to provide a priming cup through which a more volatile fuel may be admitted to produce a few initial impulses. A few drops of the priming fuel are usually squirted into the priming cup from a small oil can or similar container and the engine immediately turned over by hand or other means.

It is an object of my invention to avoid the necessity of manipulating priming means of the aforesaid nature when the engine is to be started and to provide an auxiliary supply of the more volatile priming fuel which may be carried by the engine and be automatically drawn upon only when starting the engine.

Further objects of this invention relate to economies of manufacture and details of construction as will hereinafter appear from the detailed description to follow. I accomplish the objects of my invention in one instance by the devices and means described in the following specifications, but it is evident that the same may be varied widely without departing from the scope of the invention as pointed out in the appended claims.

A structure constituting one embodiment of my invention, which may be the preferred, is illustrated in the accompanying drawing forming a part thereof, in which:

The single figure of the drawing shows in vertical cross section a portion of the cyl-

inder of an internal combustion engine together with fuel supplying and vaporizing means therefor comprising my invention.

In the drawing, similar reference numerals refer to similar parts throughout the several views.

Referring to the drawing, there is represented at 5 the upper portion of the cylinder of an engine of the "Knight" sleeve valve type having a piston 6 and sleeves 7 to control the entrance of fuel from the inlet chamber 8 and the exit of the burned gases into the exhaust chamber 9. Connecting with the inlet chamber 8 is a tubular member 10 which comprises a horizontal portion 11 and a vertical portion 12. The horizontal portion 11 has a passage therethrough in the form of two connecting truncated cones 14 and 15 forming what is commonly known as a Venturi tube. At the neck of the Venturi tube is a fuel inlet opening 17 controlled by an inlet valve 18 and connecting with a fuel pipe 19. This pipe extends down to a fuel tank 20 located in any convenient place, as for instance, in the base of the engine, a suitable ball valve 21 being shown closing the lower end of the tube. Between the horizontal and vertical portions of the tubular member 10 is a choke valve 24 which is adapted to be operated to engage a valve seat 25. This valve is adapted to make a somewhat loose fit with its seat to restrict the air intake rather than to completely close it off, the object being to increase the suction to more quickly draw the fuel up to the Venturi tube. The valve is carried by a stem 26 supported by a member 27 screw threaded into the tubular member 10 and is held in normal open position by a light spring 28 between the member 27 and a push button 29. The lower end of the vertical portion 12 terminates preferably adjacent the engine cylinder in order that the air drawn into the engine shall be warmed by the heat radiated from the engine. This part of the structure has, however, been purposely omitted from the drawing to avoid unnecessary confusion in illustrating the invention.

At one side of the Venturi tube preferably near an end thereof, there is provided an opening 30 to which connects a short tube 31 leading into a small auxiliary fuel tank 32 located above the tank 20. This opening 30, it should be noted, may connect with the Venturi tube at either side of the neck between the engine and the choke valve seat or, if preferred, may even connect directly 10 with the inlet chamber 8 of the engine.

With this apparatus, the engine would be normally operated upon one of the less volatile fuels as for instance kerosene which would be contained in the tank 20 and be 15 supplied to the engine through the pipe 19 and controlling valve 18. For starting the engine when it is cold the small auxiliary tank 32 would be filled with some more volatile fuel as for instance gasoline, benzene, naphtha or alcohol. The crank shaft of the engine would be given a few turns either by a hand crank or by some suitable starting device and the choke valve 24 held closed. Since the fuel level in the auxiliary 20 tank 32 is higher than that in tank 20, the more volatile fuel will reach the Venturi tube first and the vapor thereof will be carried into the engine to produce the initial 25 explosions. As soon as the engine has made a few revolutions, under its own power, the choke valve would be released by which time the operating fuel from tank 20 will have reached the engine and the engine will have developed sufficient heat to operate on the 30 less volatile fuel. By arranging the auxiliary fuel inlet 30 at one side of the neck of the Venturi tube as shown, the suction under normal running conditions with the choke valve open is not sufficient to draw 35 the auxiliary fuel into the engine, so that as soon as the engine is started and the choke valve is released, the auxiliary fuel falls to a level in the tube 31 below the opening in the Venturi tube and remains there 40 throughout the normal operation of the engine.

While I have described my invention in more or less detail, and as being embodied in certain precise form I do not desire or 50 intend to be limited thereto, as on the contrary, my invention contemplates broadly all proper changes, as well as the omission of immaterial elements and the substitution of equivalents therefor, as circumstances 55 may suggest or necessity render expedient.

Having thus described my invention, what I claim as new and desire to secure by Letters Patent, is:

1. In combination an internal combustion 60 engine, means for supplying fuel to said engine, means adapted to be operated in starting said engine to augment the flow of said fuel and means automatically operative to supply a different fuel when the said second means is actuated.

2. In combination an internal combustion engine, means for supplying a fuel to said engine, means for also supplying a lighter fuel to said engine and means operative in starting to restrict the air supply to said engine to cause said lighter fuel to reach 70 said engine.

3. In combination, an internal combustion engine, means for supplying a heavy fuel thereto, means for restricting the air intake 75 of said engine in starting, and means responsive to the operation of said restricting means for supplying a lighter fuel to said engine for starting purposes.

4. In combination an internal combustion engine having an inlet passage and a controlling valve therefor, means for supplying an operating fuel to said passage, and means independent of said valve dependent upon the closure thereof for supplying a priming fuel to said engine.

5. In combination an internal combustion engine, means for supplying to said engine a fuel for normal running, manually operated means for restricting the amount 80 of air supplied to said engine on starting, means for supplying a more volatile fuel to said engine, said last means being constructed to be automatically operative in response to the operation of said restricting 85 means.

6. In combination an internal combustion engine, an air inlet passage for said engine, means for admitting fuel to said passage, means for restricting the flow of air through 90 said passage, means for admitting a more volatile fuel to said passage for starting the engine, said last means being constructed to be operative only when said flow of air is restricted.

7. In combination an internal combustion engine, an air inlet tube connected therewith including a Venturi tube, said Venturi tube having a fuel inlet opening at its neck portion and having another inlet opening for 100 a more volatile fuel spaced from said neck portion and means for closing said inlet tube beyond said openings.

8. In combination an internal combustion engine having an air inlet tube, a Venturi tube forming a part of said tube and having a fuel inlet opening at its neck portion and having a second fuel inlet opening at one side of the said neck portion, a fuel tank connecting with and below said first 115 inlet opening, a second tank for a more volatile fuel connecting with and below said second fuel inlet but closer to said Venturi tube than said first fuel tank and a choke valve for said air inlet tube located beyond said Venturi tube whereby when said choke valve is closed in starting the engine, the more volatile fuel will first reach the engine and its flow will discontinue when the choke valve is released.

9. In combination, an internal combustion engine having an air inlet passage, suction controlled means for supplying a fuel thereto for the normal operation of said engine, suction controlled means for supplying a lighter fuel for starting said engine, said latter means being constructed to respond earlier than said former means to a predetermined suction and means operative in starting said engine to increase the suction.
